UNITED STATES PATENT OFFICE.

EDMUND E. BECHTOLD, OF CHICAGO, ILLINOIS.

CANOPY INSULATION.

1,186,734.

Specification of Letters Patent. Patented June 13, 1916.

Application filed January 25, 1915. Serial No. 4,113.

To all whom it may concern:

Be it known that I, EDMUND E. BECHTOLD, a citizen of the United States, residing at the city of Chicago, in the county of Cook and State of Illinois, have invented certain new and useful Improvements in Canopy Insulation, of which the following is a specification.

This invention relates to improvements in means for affording perfect insulation to canopies, such as are used for electric light fixtures or combination fixtures at their juncture with walls or ceilings of rooms or other supports therefor, and it consists in certain peculiarities of the construction, novel arrangement and operation of the parts thereof, as will be hereinafter more fully set forth and specifically claimed.

The principal object of the invention is to provide insulation for canopies and the like, which shall be of such construction and arrangement of its parts as to reduce the cost of such insulation, both as it relates to the material, and to the means or manner of installation, or its application to the canopies or parts to be insulated, as well as, to the packaging of the insulation.

Another object is to provide insulation which may be carried in stock already prepared to be readily applied to the canopy or other article, without the use of rivets or brads, yet in a firm and secure manner, and so as to effectually insulate it from its support.

A further object of the invention is to provide insulation of the above named general character, which can be coiled into compact form so as to be economically and easily shipped by mail or otherwise.

Further objects and advantages of the invention will be disclosed in the following description and explanation.

In the accompanying drawing, which serves to illustrate the invention, Figure 1 is a view in front elevation of a canopy equipped with insulation embodying the present invention, and showing it mounted on the ceiling of a room or other horizontal support and on or around a supporting pipe for a light; Fig. 2 is a vertical sectional view through a portion of the insulation and a part of the canopy showing one form of the invention; Fig. 3 is a face view of a portion of the canopy and insulating material showing a modification in the construction thereof; Fig. 4 is a sectional view taken on

line 4—4 of Fig. 3, looking in the direction indicated by the arrows; Fig. 5 is a view in elevation of a portion of the canopy and insulating material showing another modification in the construction thereof; Fig. 6 is a vertical sectional view taken on line 6—6 of Fig. 5, looking in the direction indicated by the arrows; Figs. 7 and 8 are fragmental perspective views partly in section of portions of the canopy and the insulation therefor showing other modifications in the construction of the insulation; Fig. 9 is a fragmental perspective view of a portion of the blank out of which another modification is produced, and Fig. 10 is a fragmental perspective view partly in section of portions of the canopy and insulating material constructed from the blank shown in Fig. 9.

Like numerals of reference refer to corresponding parts throughout the different views of the drawing.

The canopy or other part to be insulated from a ceiling or other support is designated by the reference numeral 10, while the ceiling or support which may be horizontal or vertical is indicated by the numeral 11. As the invention is more particularly adapted for use as a canopy insulator it is so shown in the drawing, and will be hereinafter described in such connection, but it will be understood that if desired the insulation can be employed for other articles. As shown in Fig. 1, the canopy 10 is preferably bell-shaped, and is made of metal, but may be of any suitable size and shape. The smaller end of the canopy is provided with an opening 12, to receive a supporting pipe 13, which is provided with an insulating joint 14 of the ordinary or any preferred construction, which is inclosed by the canopy. In most cases the rim or edge of the canopy adjacent to its support is slightly outwardly flared, as at 15 (see Fig. 2 of the drawing), and has at a suitable distance from said flared edge or rim an inwardly contracted portion 16, from which the material of the canopy gradually tapers to near its lower or outer extremity, in which the opening 12 is formed.

The insulation, which is designated as a whole by the reference numeral 17, is preferably made of fiber, but may be of any other suitable insulating material of thin, light and flexible nature, of any suitable dimensions. However, the fiber or insulating material 17

is by preference produced in long narrow strips, which can be rolled into compact form, similar to a ribbon, after its construction has been completed, thus enabling it to be readily packed and shipped by mail or otherwise, in small or compact packages, or, if desired, carried in stock for sale in desired lengths or quantities. In constructing the insulation, the sheet or strip 17 thereof is by preference folded or bent back upon itself at about its longitudinal middle or on a longitudinal line about midway between its edges, so that it will present an outer wall 18, and an inner wall 19 in substantial parallelism with one another. The free edge or portion of the outer wall 18 is bent or folded inwardly to form a ply 20, which is extended longitudinally with respect to the strip of insulating material 17, and has its free edge located at a suitable distance from the juncture of the outer wall 18, with the inner wall 19, yet by preference against the inner surface of the outer wall, as is clearly shown in Fig. 2 of the drawing. To prevent the strip of material out of which the insulation 17 is formed being broken by too abrupt bending at the juncture of the walls 18 and 19 thereof, and also to afford a space between said walls for the reception of a portion of the canopy and of a resting piece therefor, a cord, rod or other suitable device 21, is extended in the bend of the strip of insulating material between its walls 18 and 19, as is clearly shown in Fig. 2 of the drawing. Located between the filling piece or cord 21, and the free edge of the layer 20 of the outer wall of the fiber, is a resting strip 22, for the free or flared edge 15, of the canopy 10, or other part to be insulated. By reference to Fig. 2, it will be seen that the edge of the resting strip 22, adjacent to the layer 20, is spaced therefrom so that the flared or out-turned portion 15, of the canopy 10, may be interposed between the free edge of the layer 20 and the adjacent edge of the piece 22, as well as between the outer wall 18 and inner wall 19 of the insulating material. By this arrangement, it is obvious that the insulating material will not only be held in position on the canopy 10, or part to be insulated, by means of the flexibility or resiliency of the insulating material, but also by reason of the interlocking engagement of the layer 20 with the flared portion 15 of the canopy. While it may be preferable to employ the cord, rod or filling 21, yet I do not desire to be limited to its use, as it may be omitted, in which case the resting strip 22 for the canopy may be extended into and against the juncture of the inner and outer walls of the insulating material. In applying the insulating material to the canopy, the rim of the latter is inserted between the inner wall 19 and the layer 20 of the outer wall and forced between the same until the

flared or free portion of the edge or rim of the canopy engages the resting strip 22, in which position, it is obvious that the insulating material and canopy will be securely united.

In Figs. 3 and 4 of the drawing, is shown a modification in the construction of the insulating material, which consists in employing an outer wall 18 and an inner wall 19, formed as above described, between which walls the canopy 10 is inserted and clamped. In this modification, instead of using a resting strip 22 for the inner or free edge of the canopy or other article to be insulated, the inner wall 19 of the insulating material is provided with a series of inwardly extended tongues or members 23, which are punched out of the inner wall and extended from the latter toward or against the outer wall 18, as will be readily understood by reference to Fig. 4 of the drawing. These tongues or members 23 are arranged in a longitudinal row with respect to the strip of insulating material 17, and have their edges opposite the juncture of the walls 18 and 19 aligned, and by preference located at a suitable distance from the layer 20, of the outer wall to permit of the flared portion 15 of the canopy being inserted in the space between said parts; however it will be understood that the layer 20 may sometimes be omitted from the structure shown in Fig. 2, as well as from that shown in Figs. 3 and 4 of the drawing. The tongues 23, which form rests for the free edge of the canopy, have their ends located transversely with respect to the inner wall of the insulating material, and are shown as being arranged in diagonally and divergently inclined pairs, but it is obvious that if desired they may or may not have the divergent inclination.

In Figs. 5 and 6 is shown another modification in the construction of the insulating material, which also consists in providing an insulating material with outer and inner walls 18 and 19 respectively, the former by preference being provided with a layer 20 at its free edge, as in the other construction. In the modification now under consideration, the inner wall 19 is provided near its juncture with the outer wall 18, with a series of inwardly extended tongues 24, which have their free ends extended in alignment with one another on a longitudinal line with respect to the insulating material, in contradistinction to the transversely disposed ends of the tongues 23 of the modified construction shown in Figs. 3 and 4 of the drawing. The tongues 24 are punched out of the inner wall 19, and afford rests for the inner edge of the canopy, which is interposed between the layer 20 of the outer wall and the inner wall 19, when said layer is employed.

In Fig. 7 is shown a modification, which

is of identically the same construction as that shown in Fig. 2, and above described, except that the cord or filling 21 is omitted, and that a resting strip 25 for the canopy, of greater thickness than the resting piece 22, in Fig. 2, is employed.

In Fig. 8 is shown still another modification in the construction of the insulating material, which consists in the omission 10 from the construction shown in Fig. 7, of the layer 20 of the outer wall 18, and in providing the free edge of the outer wall 18, with an inturned shoulder or bead 26, which will engage the canopy near its free 15 edge, which free edge is adapted to rest against a resting strip 27, interposed between the outer wall 18 and the inner wall 19, and extending from the juncture of said walls toward the shoulder or bead 26, but 20 terminating at a distance inwardly therefrom.

In Figs. 9 and 10 of the drawing I have shown a modification in the construction of the blank out of which the insulation is 25 made to form the product shown in Fig. 10. In this modification the insulating material 17, is provided on one of its surfaces with longitudinally extended enlargements 28 and 29, the latter being located at the edge 30 of the outer wall 19, while the enlargement 28 is located on the inner wall near the bend or juncture of said walls, but as shown in Fig. 10, the adjacent edges of the enlarged 35 portions 28 and 29 are spaced from one another to permit of the reception of the free edge or flared portion 15 of the canopy.

In the last named modified construction, as well as in the constructions shown in Figs. 3 and 4 and 5 and 6, it is apparent 40 that all of the parts of the insulation are integral, while in the constructions shown in Figs. 2, 7 and 8 the insulation is made up of separate parts, but it will be understood that the same result of effectively and positively insulating the canopy or other part 45 from its support, and at the proper distance therefrom is accomplished by any of the constructions shown.

Having thus fully described my invention 50 what I claim as new and desire to secure by Letters Patent is—

1. Insulation consisting of a piece having an inner and an outer wall united at one of their edges, resting or stopping means for

the part to be insulated interposed between 55 said walls near their juncture, and an inwardly extended portion on the outer wall spaced from said resting or stopping means.

2. Insulation consisting of a resilient piece having an inner and an outer resilient 60 wall united at one of their edges, resting or stopping means for the part to be insulated interposed between said walls near their juncture, and an inwardly extended portion on the outer wall spaced from said resting 65 or stopping means.

3. Insulation consisting of a piece having an inner and an outer wall united at one of their edges, one of said walls having near its juncture with the other wall a series of 70 alined projections extended into the space between the walls to afford resting or stopping means for the part to be insulated.

4. Insulation consisting of a piece having approximated walls united at one of their 75 edges, one of said walls having near its juncture with the other wall a series of alined projections punched out of the wall and extended into the space between the walls to afford resting or stopping means 80 for the part to be insulated.

5. In a canopy insulation, the combination with a piece of insulating material having approximated walls united at one of their edges, one of said walls having near 85 its juncture with the other wall on its surface adjacent to the other wall resting or stopping means for the part to be interposed between said walls, and means located on the inner surface of the other wall at 90 a distance from the resting or stopping means, to engage the part to be insulated.

6. In an insulation for a canopy having a flared portion, the combination with a piece of insulating material having approximated walls united at one of their edges, of resting or stopping means integral with one of said walls near the juncture thereof, and means located on the inner surface of the other wall at a distance from the resting 95 or stopping means whereby space for the reception of the flared portion of the canopy 100 will be provided.

EDMUND E. BECHTOLD.
